 Device Corporation, Brooklyn, N. Y., a corpora-
 tion of New York

Application April 16, 1940, Serial No. 329,870

6 Claims. (Cl. 200—67)

The invention herein disclosed relates to an electric switch of the kind that is enclosed in a cabinet.

An object of the invention is to provide a switch of this kind in which there is a simple, effective and comparatively inexpensive switch operating mechanism that is reliable in operation. Another object of the invention is to provide a simple, durable and effective arrangement for effecting a snap action of the movable element of the switch. A further object of the invention is to provide a switch of this kind in which, when the cabinet is mounted on a vertical wall, the line connections are at the top of the switch and the switch-operating handle is in the up position when the switch is closed.

The foregoing objects and certain advantages that will hereinafter appear are realized in accordance with the invention in the embodiment thereof illustrated in the accompanying drawings and described in detail below. The drawings include the following figures:

Fig. 1 which is a plan of the switch with the cover of the cabinet removed;

Fig. 2 which is a transverse sectional elevation of the same taken on the line 2—2 of Fig. 1;

Fig. 3 which is an isometric of a bearing bracket;

Fig. 4 which is a bottom plan taken on the line 4—4 of Fig. 2;

Fig. 5 which is a sectional end elevation taken on the line 5—5 of Fig. 2; and

Fig. 6 which is a sectional elevation taken on the line 6—6 of Fig. 2.

The switch illustrated in the drawings is mounted within a cabinet that is made of sheet metal and that includes a rear wall 1, side walls 2 and 3, and a cover 4. Through the cover there is a slot 5 and the wall 3 is provided with an inwardly extending bearing boss 6. Within the cabinet there is a switch-operating handle 7 that is secured by, and rotatably mounted between its ends on a rivet 8 that extends through aligned openings in the boss 6 and the operating handle. The switch-operating handle is stamped from heavy sheet metal, shaped as shown (Fig. 6) and includes a finger piece 9 that extends through the slot in the cover and an extension 10 on each side of the finger piece that serve to close the slot in the cover in the two positions ("off" and "on") of the handle. In the inner portion of the operating handle, there is an arcuate slot 11 convexed toward the axis of movement of the handle. On the cover there is a raised strip 12 which in the "off" position

of the operating handle is beside a sealing opening 13 through the operating handle.

Within the cabinet, there are mounted two identical fuse-switch units 14 and 15 which are operated conjointly and represent a double pole switch. The unit 14 is represented in outline by the broken line as it is identical with the unit 15. The unit 15 comprises a base 16 of electrical insulating material on which there is formed a screw plug fuse receptacle 17. About the fuse receptacle 17 there is a shoulder 18. The base is secured in the cabinet by two screws 19 which extend through an opening in the base and are threaded into the rear wall of the cabinet. On the upper portion of the shoulder 18, considering the switch as mounted vertically, there is secured to the base a neutral fitting 20 which is riveted in place on the base by rivets that are molded in the base. The neutral fitting includes a section 20a which has two terminal screws 21 thereon. The neutral fitting also includes an extension 20b to which there is secured a solderless connector 22. A barrier 23 extends from the fuse receptacle 17 adjacent the extension 20b of the fitting 20.

On the opposite side of the barrier, there is mounted on the base a stationary switch contact 24. This stationary switch contact lies in a vertical plane perpendicular to the plane of the base 16 and it has an extension 25 which lies along the surface of the shoulder 18. This extension 25 is secured to the base by a rivet or screw 26. On the end of the extension 25, there is mounted a solderless connector 27. The line wires are connected to the solderless connectors 22 and 27. The stationary switch contact 24 is shaped as illustrated and extends to a point adjacent the lower end of the fuse receptacle and the end thereof extends into an arc chute 28 formed on the base at one side of the fuse receptacle.

Another stationary contact 29 is mounted in a vertical plane perpendicular to the plane of the base, and spaced from the contact 24. The end of this contact also extends into the arc chute 28. The contact 29 has an extension 30 that extends into the fuse receptacle wherein it is secured to the base. The extension 30 is spaced from the base of the receptacle and is above an insulating washer 31 within the fuse receptacle. It is secured in the fuse receptacle and to the base by a rivet 32 that extends from a boss 33 upon which the extension rests. At the end of the extension 30 there is a raised portion 34 which is substantially at the center of the fuse receptacle. This raised portion 34 of

the extension 30 constitutes the center contact of the fuse receptacle.

Within the fuse receptacle, there is a screw plug shell 35 having standard threads rolled therein to receive a screw plug fuse. The base of the shell rests upon the base of the receptacle, a suitable opening being provided through the base of the shell to receive the bosses 33 and through the side to pass the contact extension 30. On top of the base of the shell and electrically connected therewith there is a connector 36 which has an opening through which the boss 33 extends. The insulating washer 31 covers the base of the shell and that portion of the connector 35 within the fuse receptacle and so electrically separates the extension 30 of the contact 29 from the shell and the connector 36. The connector 36 extends through a slot in the shell and fuse receptacle to the lower end of the base 16 and has therein a terminal screw 37.

In assembling the fuse receptacle, the shell 35 is first placed in the receptacle. The connector 36 is next placed in position. The washer 31 is then placed in the fuse receptacle and the extension 30 of the contact 29 is assembled in the receptacle. The one rivet 32 secures the entire assembly in place. It will be seen that through the raised portion 34 of the extension 30 the center contact on a fuse inserted in the fuse receptacle will electrically engage the raised portion 34 and thus effect an electrical connection with the contact 29. By virtue of the contact of the connector 36 with the shell 35, the connector 36 forms a second contact with the fuse receptacle.

Between the contacts 24 and 29, there is a movable switch element 38 consisting of a sheet of electrical insulating material. This movable element includes a contact 39 which consists of a single piece of electrical conducting material that extends through a slot formed in the movable element 38 and that is bent over forming two wings one lying against each side surface of the movable switch element 38. The switch element 38 is movable between a position in which the contact 39 is between and bridges the stationary switch contacts 24 and 29 to a position in which the contact 39 is removed from between the contacts 24 and 29. In this latter position, the contacts 24 and 29 are separated by the strip of insulating material that constitutes the movable switch element. This switch element is movable from the position shown in Fig. 5, which illustrates the switch element in the "on" position to a position indicated by the center line 40 which is the "off" position of the switch. It will be seen that in moving the switch element from the "on" to the "off" position, the contact 39 thereon moves into the arc chute 28 and any arc that is formed in the opening of the switch will be formed in the arc chute.

The movable element 38 together with the movable switch element of the switch unit 14 is actuated through a cross bar 41 upon which it is mounted. The cross bar 41 is journaled in a bearing bracket 42 that is received in a recess provided therefor at the rear of the base 16 and in a similar bearing bracket in the switch unit 14. The bearing bracket consists of a piece of sheet metal shaped as illustrated in Fig. 3 to include two walls 42a and 42b and a connecting wall 42c, the bracket being substantially U-shaped. In the walls 42a and 42b there are provided bearing openings 43a and 43b respectively. Communicating with the opening 43a there is a slot 44

extending from the edge of the side wall. A similar slot 45 communicates with the bearing opening 43b. In the connecting wall 42c, there is a transverse raised section 46 centrally thereof. Through this central section there is an opening 47.

The cross bar 41 is rectangular in end elevation. At one edge, below the switch unit 14, it is notched at two spaced sections 48 and 49. The opposite edge is similarly notched at 50 and 51 and between these notches there is a central cut-out section 52. Beneath the unit 15 the cross bar is similarly notched, the notched sections being indicated by the same numerals primed. The cross bar is inserted in the bearing bracket at the points 48' and 49', at which points the cross bar is reduced in width, by being slipped through the slots 44 and 45. The cross bar is entered in the slots edgewise. When received in the bearing openings 43a and 43b and turned, it is held within the bearing openings. With the cross bar in the bearing openings, the bearing bracket is inserted in the receptacle in the base of the switch unit. It is secured thereto by a rivet 53 which is molded into a boss 54 extending into the bearing bracket receiving receptacle and engaging the raised portion 46 of the bearing bracket. The cut-out section 52 in the cross bar receives the boss 54. The cross bar is thus journaled at two spaced points in each switch unit and it is supported by the switch units. It extends through the movable switch elements, from one side of the switch unit 15, through the slot 11 in the switch-operating handle 7 and into an opening 55 provided therefor in the side wall 3 of the cabinet.

The slot 11 is an arc of a circle the center and radius of which are arranged with respect to the axis of angular movement of the switch-operating handle 7 so that successive points on the center line of the slot 11 pass the axis of rotation of the cross bar 41. Since the cross bar is restrained to angular movement, by the bearing brackets in the switch units and the opening 55 in the wall 3, about its longitudinal axis, movement of the switch-operating handle 7 about the axis of the rivet 8 causes the cross bar to assume successive positions as a chord of the circle represented by the slot and so effects angular movement of the cross bar in the same direction as the switch-operating handle. In this way the movable switch elements of the switch units through which the cross bar extends are caused to move, upon movement of the switch-operating handle, from a position in which the contacts thereon bridge the stationary contacts to a position in which the contacts thereon are within the arc chutes and the insulating material separates the stationary contacts.

To effect a snap action of the switch-operating handle and in consequence the cross bar and movable switch elements, a spring 56 is provided. This spring consists of a single piece of bent spring steel wire shaped, when under tension, substantially as shown and lying in a single plane. One end 57 of the spring is slidably mounted in an opening in one leg 58 of an L-shaped bracket 59 secured to the inner surface of the wall 3 of the cabinet. The other end of the spring is received in an opening in an arm 60 extending from the edge of the switch-operating handle. It will be seen that the spring tends to straighten out and that when the operating handle is midway between its two positions of movement the spring is contracted the greatest amount. In consequence, as the switch-operat-

ing handle passes its mid-position moving in either direction it is snapped to the position in which it is traveling.

The switch described is of the kind that is commonly used on a vertical wall. It will be noted, that when the switch is mounted vertically the solderless connectors 22 and 27 are at the top of the switch so that the line wires enter at the top of the cabinet and are connected at the top of the switch. In addition, the switch is so arranged that when mounted upon a vertical wall the operating handle is in the up position when the switch is on. It has been a problem to reconcile these two features as is thus accomplished in the switch illustrated and described. It will be apparent that with this switch construction multiple pole switches and single pole switches are readily arranged in accordance with the number of switch units utilized.

It will be obvious that various other modifications and changes in the details of the embodiments of the invention illustrated in the drawings and described above may be made by those skilled in the art within the principle and scope of the invention as expressed in the appended claims.

We claim:

1. A switch of the kind described comprising in combination a switch unit including a base of electrical insulating material, a pair of spaced, stationary electrical contacts mounted on the block of insulating material, a U-shaped bearing bracket having aligned bearing openings in the leg portions thereof secured to the underside of the base, a cross bar rectangular in end elevation having reduced sections journaled in the bearing openings in said bearing bracket and extending from the side of the base, a movable switch element positioned to bridge the stationary contacts and secured to the cross bar for movement therewith and a contact on the movable switch element arranged to engage both stationary contacts in one position of the switch element, and a rotatably mounted operating handle connected to the cross bar.

2. A switch of the kind described comprising in combination a switch unit including a base of electrical insulating material, stationary electrical contacts mounted on the block of insulating material, a U-shaped bearing bracket having aligned bearing openings in the leg portions thereof and communicating slots extending from the edges thereof secured to the under side of the base, a cross bar rectangular in end elevation having reduced sections journaled in the bearing openings in said bearing bracket and extending from the side of the base, a movable switch element arranged to bridge the stationary contacts and secured to the cross bar for movement therewith and a contact on the switch element positioned to engage the stationary contacts in one position of the switch element, and a rotatably mounted operating handle connected to the cross bar.

3. A switch of the kind described comprising

in combination a switch unit including a base of electrical insulating material having a bearing bracket receptacle in the base thereof, stationary electrical contacts mounted on the block of insulating material, a U-shaped bearing bracket having aligned bearing openings in the leg portions thereof and communicating slots extending from the edges thereof secured to the under side of the base and extending into the aforesaid receptacle, a cross bar rectangular in end elevation having reduced sections journaled in the bearing openings in said bearing bracket and extending from the side of the base, a movable switch element arranged to bridge the stationary contacts and secured to the cross bar for movement therewith and a contact on the switch element positioned to engage the stationary contacts in one position of the switch element, and a rotatably mounted operating handle connected to the cross bar.

4. A switch of the kind described comprising in combination a switch-operating handle mounted for angular movement and having an arcuate slot therethrough eccentric to the axis of movement of the handle, a switch unit including a base of electrical insulating material, a pair of spaced, stationary switch contacts mounted on the base, a rotatable cross bar rectangular in end elevation extending from one side of the base, through the arcuate slot in the switch-operating handle and engaging the edges thereof, a movable switch element secured to the cross bar, and a contact on the movable switch-element arranged to engage and bridge the stationary contacts in on position of the movable switch element.

5. A switch of the kind described comprising in combination a switch-operating handle mounted for angular movement and having an arcuate slot therethrough at one side of the axis of movement of the operating handle and convexed towards the axis of movement of the operating handle, a switch unit including a base of electrical insulating material, a pair of spaced, stationary switch contacts mounted on the base, a rotatable cross bar rectangular in end elevation extending from one side of the base, through the arcuate slot in the switch-operating handle and engaging the edges thereof, a movable switch element secured to the cross bar, and a contact on the movable switch element arranged to engage and bridge the stationary contacts in on position of the movable switch element.

6. In a switch of the kind described the combination comprising a switch-operating handle pivotally mounted between its ends and having an arcuate slot therethrough eccentric to the pivotal axis thereof, and a rotatably mounted switch operating bar having a width greater than the thickness thereof and greater than the width of the slot in said operating handle, the bar extending into the arcuate slot in the handle.
